(No Model.)

H. FLATER.

SAW SET.

No. 269,402.

Patented Dec. 19, 1882.

Fig. 1.

UNITED STATES PATENT OFFICE.

HENRY FLATER, OF FINDLAY, OHIO, ASSIGNOR OF ONE-HALF TO JOHN POE.

SAW-SET.

SPECIFICATION forming part of Letters Patent No. 269,402, dated December 19, 1882.

Application filed August 23, 1882. (No model.)

To all whom it may concern:

Be it known that I, HENRY FLATER, a citizen of the United States of America, residing at Findlay, Hancock county, State of Ohio, have invented certain new and useful Improvements in Saw-Sets, of which the following is a specification, reference being had therein to the accompanying drawings.

Figure 1 is a plan view. Fig. 2 is a side elevation. Fig. 3 is a longitudinal vertical sectional view, and Figs. 4 and 5 are vertical cross-sections.

This invention has relation to saw-sets; and it consists in the construction and novel arrangement of parts, as will be hereinafter fully described, and particularly pointed out in the claims appended.

The object of this invention is to give a uniform set to any saw, from a fine handsaw to a large crosscut-saw.

Referring by letter to the accompanying drawings, *a* designates the base-plate, provided with the clamping-arm *b*, having the clamping-screw *c* near its middle portion and the perforated ears *d* at one end, through which wood-screws are to be passed to secure it to the bench, to hold it, in connection with the clamping devices, securely in place on the bench. In plan view the base *a* is nearly in cross form, the edges of the transverse portion being recessed at *e*, and having the upper and lower inner faces *ff'* of this portion provided with vertical horizontal grooves *g g'*, the inner walls of which are in line with the vertical walls of the recesses *e*, as shown in the drawings. A recess, *e'*, extends from each recess *e* to a recess, *h*, in each edge of the stem portion *h'* of the base *a*, and vertical longitudinal grooves *i i'* are formed in the inner faces *jj'* of the projections *k k'*, as shown. The stem portion *h'* has a lateral slot, *l*, somewhat elongated, about the middle of its length, for the reception of a lateral bolt, *m*, the purpose of which will be hereinafter explained. The base portion just described is preferably made of malleable iron, and is provided with a graduated scale, *n*, upon its face, at one side, as shown, and is recessed longitudinally in the middle of the transverse portion to receive an anvil, *o*, of steel, said anvil having a beveled front end, *o'*, which comes under the head of the pivoted jaw *p*. The head *p'* of this jaw is

also of steel, and is pointed, and has an under bevel, *q'*, as shown, to correspond with the bevel *o'* of the anvil. A spring, *r*, is let into a recess, *s*, in the stem portion *h'*, and has its upper end in engagement with the under face of the pivoted jaw *p* for the purpose of lifting the jaw after each blow upon its head.

t designates a sliding gage having arms *t'* and *t''*, which are provided on their upper and lower edges with vertical flanges *u*, which fit and work in the vertical grooves *g g'* and *i i'*. The arms *t' t''* are provided on their outer faces, near or at their front ends, with vertical standards *v*, which carry on their rear edges guards *v' v'* of brass, against which the saw-teeth rest when being set. The arms *t''* are perforated laterally at *w* for the reception of a bolt, *m*, which passes through them and through the elongated lateral slot *l* in the stem portion *h'* of the base *a*. This bolt *m* is provided with a thumb-nut, *m'*, for locking the sliding gage in any position to which it may have been adjusted. The rear end of the sliding gage is provided with a vertically-adjustable screw, *x*, for elevating or lowering the back of cross-cut-saws when they are being set, so that the desired angle may be given to the teeth of the same.

The operation of the device is very simple, and is as follows: The device is first securely fastened to the bench. The sliding gage is then adjusted by the scale to the grade of set desired. The points of the saw-teeth are then pressed against the brass guards and the head of the jaw driven down on each alternate saw-tooth by a blow from a hammer or hatchet. The alternate teeth which have not been struck should be operated upon in a like manner from the other face of the saw.

Having thus fully described my invention, what I claim as new, and desire to secure by Letters Patent, is—

1. In a saw-set, the combination, with the base-plate *a*, having the clamping-arm *b*, clamping-screw *c*, and perforated ears *d*, of the anvil *o*, having the bevel *o'*, and the pivoted jaw *p*, having the head *p'*, with under bevel *q'*, and the spring *r*, substantially as and for the purpose specified.

2. In a saw-set, the base-plate *a*, recessed and grooved in its edges and having the lateral slot in its stem portion *h'*, the graduated

scale, and pivoted spring-actuated jaw, in combination with the sliding gage carrying the tooth-guards, and the adjusting-bolt and thumb-nut, substantially as and for the purposes specified.

3. In a saw-set, the combination, with the base-plate carrying the beveled anvil, the graduated scale, and pivoted spring actuated jaw, of the sliding gage carrying the tooth-

guards, and the vertical adjusting-screw x , substantially as and for the purposes set forth.

In testimony whereof I affix my signature, in presence of two witnesses, this 16th day of August, 1882.

HENRY FLATER.

Witnesses:

ANTHONY J. SANDERS,
PAUL KEMERER.
